UNITED STATES PATENT OFFICE.

CLAYTON M. BOUDETTE, OF REVERE, MASSACHUSETTS.

DESIGN FOR A RADIO LOUD-SPEAKER BODY.

Application filed October 2, 1926. Serial No. 19,227. Term of patent 7 years.

To all whom it may concern:

Be it known that I, CLAYTON M. BOUDETTE, a citizen of the United States, residing at Revere, in the county of Suffolk and Commonwealth of Massachusetts, have invented a new, original, and ornamental Design for a Radio Loud Speaker Body, of which the following is a specification, reference being had to the accompanying drawing, forming a part thereof.

Figure 1 is a view in front elevation showing my new design;

Fig. 2 is a view in rear elevation; and

Fig. 3 is a view in side elevation.

The dominant feature of the design comprises an outer frame having an octagonal perimeter and a circular opening. The shading on the drawing within the circular opening represents a textile fabric gathered to a central button.

I claim:

The ornamental design for a radio loud speaker body substantially as shown and described.

CLAYTON M. BOUDETTE.
